UNITED STATES PATENT OFFICE.

GEORGE D. KRATZ AND CHARLES WATTLEWORTH, OF AKRON, OHIO, ASSIGNORS TO THE FALLS RUBBER COMPANY, OF CUYAHOGA FALLS, OHIO, A CORPORATION OF OHIO.

DESIGN FOR A TIRE.

Application filed June 9, 1922. Serial No. 2,594. Term of patent 7 years.

To all whom it may concern:

Be it known that we, GEORGE D. KRATZ and CHARLES WATTLEWORTH, citizens of the United States, and residents of Akron, county of Summit, and State of Ohio, have invented a new, original, and ornamental Design for a Tire, of which the following is a specification, reference being had to the accompanying drawing, forming part thereof.

In said annexed drawing:—

Fig. 1 is a plan view of a portion of our tire; and Fig. 2 is a section on the line 2—2 of Fig. 1.

We claim:—

The ornamental design for a tire as shown.

Signed by us, this 6th day of June, 1922.

GEORGE D. KRATZ.
CHARLES WATTLEWORTH.
